UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

DRY-PIPE-VALVE ACCELERATOR.

Application filed March 1, 1921. Serial No. 448,880.

The present invention relates to an apparatus for hastening the delivery of water to an automatic fire extinguishing system after the opening of one or more of the 5 sprinkler heads thereof, and one object of this invention is to provide an apparatus which shall reduce to a minimum the time elapsing between the reduction of air pressure in the system resulting from the opening 10 of a sprinkler head, and the time when the dry pipe valve operates to permit flow of water under pressure into said system.

A further object of the invention is to provide an apparatus of this character which 15 will be responsive to a very slight reduction of the pressure in the sprinkler system, which is constructed in a very simple manner so that the same is not likely to become disarranged, and which may be operatively 20 connected to sprinkler systems of the dry pipe type now in use, with a minimum of expense and alteration.

A further object of the present invention is to provide an apparatus of this character 25 which will operate in a very certain, as well as rapid manner, the parts of which may be readily returned to normal position when desired.

These objects and other advantageous ends 30 I attain as hereinafter set forth, reference being had to the accompanying drawings, in which,

Fig. 1 is a view partly in elevation and partly in section of an apparatus constructed in accordance with the present invention, the same being applied to the dry pipe valve assembly of a sprinkler system;

Fig. 2 is a vertical section of the present apparatus; and

Fig. 3 is a vertical section on a plane at right angles to that of Fig. 2.

Referring to the drawings, the numeral 1 indicates the casing of a dry pipe valve assembly now commonly used in automatic 45 sprinkler systems. The casing 1 is divided into two chambers 2 and 3, the former being the pressure chamber and communicating at its upper end with the conduit 4 which leads to the sprinkler heads located in various 50 parts of the building or other structure. The conduit 4 and the chamber 2 are normally filled with air under pressure, the escape of this air being prevented when the valves at the sprinkler heads are in their

normal closed position. A partition 1^a separates the chamber 2 from the chamber 3 and the latter is known as an intermediate chamber and contains air under atmospheric pressure. The chamber 3 communicates at its lower end with the conduit 5 which leads to the fire extinguishing fluid supply; and communication between the conduit 5 and the chamber 3 is normally closed by means of the valve 6 held to a suitable seat. Communication between the chambers 2 and 3 is normally closed by the air valve 7 which has a relatively broad surface projecting into the chamber 2, against which surface the air under pressure in said chamber 2 will act to normally close the valve 7 tightly against its seat. The valve 7 is rigidly connected to the valve 6 by means of an arm or rod 8, and this arm 8 has an off-set portion 8^a which carries at its extremity a suitable pivot means 8^b. It will therefore be seen 75 that any movement of the valve 7 is transmitted to the valve 6, and the valve 6 cannot open until the valve 7 is likewise permitted to open.

In the normal operation of a valve assembly such as has been described, the air under pressure in the chamber 2 acting against the broad top surface of the valve 7 will hold said valve firmly pressed to its seat and through the arm 8 will also hold the valve 6 to its seat against the pressure of the water in the conduit 5. The water in the conduit 5 is therefore prevented from entering the chamber 3 and the sprinkler system so long as the valve 6 is held to its seat by the air pressure on the valve 7. Upon the release of the pressure in the chamber 2 by reason of the opening of one of the sprinkler heads of the system, the pressure upon the valve 7 becomes lessened and when the pressure within the chamber 2 reaches the point when it is insufficient to hold said valve closed against the pressure of the water in the conduit 5, the valves 6 and 7 will open and water will flow from the conduit 5 into the chambers 3 and 2 and into the pipes of the system to the open sprinkler head. This is the well known operation of this type of valve assembly, and it has been found that an appreciable length of time will elapse before the pressure in the chamber 2 has been sufficiently reduced to permit the valve 6 controlling the water supply to open. Since

time is of the utmost importance it has become necessary to devise some means for quickly releasing the pressure in the chamber 2 and allowing the water to enter the system.

The present invention is constructed with a view to a quick release of pressure in the chamber 2 and a quick equalization between the pressure in the chambers 2 and 3 so that the valves 6 and 7 may be opened in the shortest possible time. To that end I provide an apparatus having certain of its parts in communication with the chambers 2 and 3, and this apparatus comprises an outer casing 10, this casing being internally divided into three compartments, communication between the compartments being provided by suitable valve devices. The main compartment within the casing 10 is indicated by the numeral 11, and this compartment is in communication with the chamber 2 through a suitable pipe 9. A second compartment 12 is disposed beneath the main compartment 11 and the compartment 12 is in communication with the chamber 3 through a suitable pipe 12^a. The third compartment within the casing 10 is disposed at the upper portion of the same and this latter compartment 13 has no direct communication with any part of the valve assembly.

The chambers 11 and 13 are in communication by means to be hereinafter described so that air pressure in one compartment may proceed to the second compartment in the operation of this apparatus. Disposed within the upper portion of the casing 10 is a bellows 14 carrying at its upper end a cover plate 15 having a nipple 16 projecting therefrom, the nipple 16 being internally screw-threaded to receive the plug 17 carrying as a part thereof a hexagonal nut to facilitate rotation of the same. The plug 17 is internally screw-threaded to a portion of its depth and the unthreaded portion of said plug is adapted to receive a series of washers 18 adapted to compress between them a series of discs, in the present instance three, the central disc 19 being solid with the exception of a small opening in its center. On either side of the disc 19 are the filter discs 20 which serve the purpose of preventing foreign matter from reaching and clogging the opening in the disc 19. The assembly of discs and washers is held in place by a second plug 21 which is adapted to be screw threaded into the threaded portion of the plug 17 until its lower ends engage the topmost washer, and thereby firmly hold the washers and discs in position. The plug 21 has a vent 21^a through its upper surface to permit the passage of air under conditions of operation.

The bellows 14 extends from the top plate 15 to the partition plate 22 and is clamped to said plate by suitable bolts 23. The par-

tition plate 22 in the present instance is shown as being clamped between two portions of the casing 10 and is held in such clamped position by means of suitable bolts 24 or other fastening devices. The partition plate 22 has a series of openings 22^a therein and a central opening 22^b through which extends the rod 25, said rod 25 being carried by and depending from the top plate 15 of the bellows. Openings 15^a are disposed in the top plate 15 to permit communication between the interior of the bellows through the opening in the disc 19 to the compartment 13.

The partition 22 carries depending spaced arms 22^c, and a pin or rod 26 is mounted within and supported by openings in the arms 22^c. Pivotedly mounted on the pin 26 is an arm 27 having opposite projections 27^a, 27^b, the projection 27^a being adjacent the lower extremity of the rod 25 carried by the bellows. The projection 27^b is disposed adjacent the top of a pivoted weight 28, the said weight being supported at its lower extremity upon suitable pins 29 supported by arms 30^a.

Between the compartments 11 and 12 is a suitable opening 11^a and disposed within this opening is a sleeve 30 having a flange 30^b resting upon the top surface of the partition 12^b dividing the compartments 11 and 12. A suitable nut 31 is threaded upon the lower end of the sleeve 30 and firmly clamps the same in proper position within the opening 11^a. The arms 30^a, previously described, project from the sleeve 30 and support the pins 29 upon which the pivoted weight 28 is mounted. The opening in the sleeve 30 is normally closed at its upper end by a suitable valve 32, and this valve is held in the closed position by the pressure of an arm 33 pivotally mounted upon a projection 30^c of the sleeve 30, the said arm 33 being held in engagement with the valve 32 by the weight 28, the lower portion of which normally rests against the arm 33. Extending through the sleeve 30 and bearing against the under surface of the valve 32 is provided a rod 34 having its upper surface rounded at 34^a as shown, the rounded end 34^a contacting with the lower surface of the valve 32, said lower surface of the valve being dished at its center, and the rounded end of the rod 34 being normally disposed against the dished face of the rod 32. The lower end of the rod 34 is somewhat rounded at 34^b and carries at said lower end a pivoted link 35 supported by arms 36 projecting upwardly from the lower surface of the casing. The link 35 carries at its other end a weighted valve 37, which valve is adapted to seat upon the upper surface of a vent plug 38 to close the same and thereby prevent communication between the compartment 12 and the atmosphere.

In the operation of the present invention the chamber 2 being filled with air under pressure this air under pressure will pass through the pipe 9 into the compartment 11, and from said compartment through the openings 22^a, 15^a, through the opening in the disc 19 and through the vent 21^a into the compartment 13. The bellows 14 will be in the expanded position as shown in Fig. 2, and the rod 25 will be upwardly withdrawn in the position as shown in said figure. The weight 28 will be in the position shown in Fig. 2, with its lower end bearing against the pivoted arm 33 and thereby holding the valve 32 firmly against its seat. The valve 32 being seated will bear against the upper end of the rod 34 and the link 35 will have been turned on its pivot to raise the valve 37 away from the vent 38 so that the air pressure within the chamber 12, by reason of the latter's communication with the atmosphere through the vent 38, will be atmospheric. Upon the reduction of the air pressure within the compartment 2 due to the opening of one of the sprinkler heads of the system the air pressure will be immediately lessened in said chamber 2 and in the compartment 11 of the casing 10. The air pressure in the compartment 11 and in the bellows 14 having been lessened the air pressure within the compartment 13 will immediately be in excess of that in the compartment 11, and this pressure in the compartment 13 acting upon the top plate 15 of the bellows will force the bellows to contract, and the plate 15 carrying the rod 25 will be moved downwardly. The rod 25 will contact with the projecting portion 27^a of the pivoted arm 27 and will swing the said arm on its pivot, whereupon the projection 27^b of said arm will engage the weight 28, and upon continued movement shift said weight on its pivot toward the left as is evident from the showing in Figure 2, the weight dropping to the shifted position very quickly upon the predominant mass of the same passing the vertical center line of its pivot. The weight being released from engagement with the arm 33 the valve 32 will be free to open due to the weight carried by the link 35 and the valve 37 will become seated against and close the vent 38. The compartments 11 and 12 are thereupon brought into communication and the excess of air pressure in the compartment 11 will pass through the sleeve 30 into the compartment 12 and thereafter through the pipe 12^a into the chamber 3. There is now communication through the pipe 9, compartments 11 and 12 and pipe 12^a between the chambers 2 and 3, and the pressure within these two

chambers will immediately become equalized. The water under pressure in the conduit 5 bearing against the valve 6 will now force said valve upwardly, since the air pressure 65 upon the top surface of the valve 7 has been released, and water will pass from the conduit 5 into the chambers 3 and 2 and into the conduit 4 to the open sprinkler head.

During the passage of water through the 70 sprinkler system air will be continuously passing through the opening in the disc 19 from the chamber 13 into the chamber 11, this passage of air being necessarily at a very slow rate due to the small size of the 75 said opening. Upon the gradual release of the pressure within the compartment 13 the bellows 14 will expand to normal position and the rod 25 will be withdrawn. Upon the stoppage of the flow of water, when it 80 is desired to reset the apparatus for further operation, the cover plate 40 (Fig. 3) is removed permitting access to the interior of the compartment 11, and by suitably inserted means the weight 28 is tipped to the 85 normal position shown in Fig. 2. Upon the replacement of the cover plate 40 air under pressure may be introduced into the sprinkler system and into the chamber 2 whereupon it will pass into the compartment 11 and 90 through the opening in the disc 19 into the compartment 13 until the pressures in the compartments 11 and 13 are equalized. The apparatus is now ready for subsequent use in the manner specified. 95

It will therefore be seen that I have devised an apparatus of this character which will quickly and readily operate to perform the desired functions, and which will be very positive in its action, allowing no possibility to prevent its operation in the required manner. 100

I claim:

In an accelerator the combination of a casing divided into a plurality of compartments, one of said compartments being in communication with the air chamber of a dry pipe valve, and another of said compartments being in communication with the intermediate chamber of the said dry pipe 105 valve; a valve controlling communication between said two compartments; a vent in said second named compartment; a weighted means for actuating said controlling valve; means operative upon a reduction of air 110 pressure within the air chamber of the dry pipe valve for actuating said weighted means; and vent-closing means normally held in open position and operative on the opening movement of said controlling valve 115 to close said vent. 120

ARTHUR C. ROWLEY.
